UNITED STATES PATENT OFFICE.

OLIVER M. BABCOCK, OF EVANSTON, ILLINOIS.

CONTAINER.

Application filed January 18, 1924. Serial No. 686,957.

The present invention relates to containers, of the kind for including packaged goods or goods packages.

Among the objects of the invention are 5 to provide a novel container which will be capable of use as a shipping container, box, crate or the like for contained packages, cans and similar articles; which will be of unusual light weight combined with increased 10 strength; which will be commercially practical for the purposes mentioned, as well as for other uses hereinafter appearing; which comprises side walls having wall members, preferably of thin sheet material, 15 such as wood, fibre board and other like and similar materials, and reinforcing elements adhering or being joined thereto, throughout a substantial portion of their surfaces of contact with the wall members, such joining, in a specific form of the invention, being 20 by way of gluing, whereby the stretching or shrinking, and hence cracking or splitting of the members, as well as warping and other deformations, are prevented, this being of 25 particular advantage where the wall members are of thin wood, such as rotary cut lumber; which has the reinforcing elements so arranged and spaced as to give the container maximum strength for minimum 30 weight; which has the reinforcing elements so located, preferably inside of the container, whereby the outer faces of the container are left smooth and without any projections, thus avoiding the heretofore catching of 35 projections of a container upon another with the result of breaking the container open and attendant damage to or loss of the goods and the like, also avoiding injury to those handling the containers, also the facilitating 40 of even piling and packing of containers in a car, storage space, or the like, and, further providing convenient and unobstructive surfaces for the appearance of printed and advertising matter, as well as brand titles 45 of the goods upon the container; which has the reinforcing elements or strips so located that they also act as spacing or packing guides as well as supporting members for the goods packages to the end that the packages 50 are compactly held in place, each strip being located where the adjacent boundaries of the packages meet, as for example, the strips on the bottom wall lie under the adjacent edges of adjacent packages, the strips on the side walls overlap the top and lower side edges of adjacent packages, and, the 55 strips on the top wall rest upon the adjacent top edges of adjacent packages, this arrangement thus providing for supporting or holding the packages in their proper positions and in compact space, and also providing for air spaces between the packages and the inner face of the outer wall member, whereby air circulation within the container and around the packages is permitted to the 60 end that when the goods have been moved from a colder to a warmer atmosphere and humidity has condensed upon the surfaces of the packages, the circulation of air in the container may evaporate and carry off the 65 moisture rather than permitting it to remain and eventually corrode or otherwise damage the packages, or possibly the container itself; which has the strips also so arranged that the packages will be held spaced away 70 and at a distance from the wall members so that any blow or impact upon the wall members from any external object, or even the piercing of such wall members thereby, as by a hook, will not be transmitted or felt 75 by the packages owing to the spaces between the wall members and the packages providing room for whatever deflecting the wall members may receive from the impacts or 80 blows or for the play of the end of the hook, if the latter pierces the wall member; which has the strips of one wall so arranged and located with respect to the strips of the adjacent wall that fastening members, such as 85 nails, staples, and other like and similar 90 fastening devices, with or without corner strips, or the like, may be driven both through the wall member and the attached strips of one wall into the strips of the adjacent wall, without any splitting or cracking 95 of the wall members; which have, in one form of the invention, the strips of one or more walls such as the side wall, provided with notches for receiving the strips of the adjacent wall, thus increasing the rigidity 100 and strength of the container as a whole, the walls being connected together with the same effect as if they were dove-tailed together; which has, in an embodiment of the invention, the strips of either or both top 105 or bottom walls resting on or against the edges of the side walls so as to provide air spaces or passages between said side walls or the top or bottom walls; which has end walls with means, such as notches, in the 110 edges of the end wall pieces, if the latter be solid, or in cleats attached to the end wall

members, if the latter be thin sheet material, for receiving or securing therein of the reinforcing elements of the side walls, or, more specifically speaking, the ends of the strips of the side walls are mortised and tenoned to the edges of the end walls, whereby the container has greater rigidity and strength; which is so constructed that the cover may be readily removed without injuring the cover or the remainder of the container, and that the container may be used as a delivery container or receptacle in lieu of baskets, boxes, and the like heretofore used, the container of the present invention being as light in weight as a basket and yet as strong as a box made of much heavier material; and, which has such other and further objects, advantages and capabilities as may later appear and are inherently possessed by the invention.

In the drawings, illustrating certain embodiments of the invention, Fig. 1 is a perspective view of a container, with the cover in place; Figs. 2 and 2^a are similar views with the cover removed and showing the interior of the container partly packed with goods packages and showing the mode of packing; Fig. 3 is a dissected perspective detailed view of the container; Fig. 4 is a perspective view of the solid end wall which may be used in lieu of the end wall shown in Fig. 3; Fig. 5 is a top plan view of an open container fully packed with cylindrical type of goods packages; Fig. 6 is a side view of the container with the cover in place; Fig. 7 is an end view of the same; Fig. 8 is a horizontal sectional view of the container with packages in place; Fig. 9 is a vertical longitudinal sectional view of the same; Fig. 10 is a vertical transverse sectional view of the same; Fig. 11 is a top plan view of a modification and showing a use of rectangular type of packages; Fig. 12 is a vertical longitudinal sectional view of the same; Fig. 13 is a fragmentary perspective view of a form showing air spacing between a top (or bottom) wall and a side wall; and, Fig. 14 is a fragmentary sectional view of the same.

Referring now more particularly to the forms shown in Figs. 1 to 10 inclusive, the container is shown as having top and bottom walls 1, side walls 2 and end walls 3. All walls are made with each a thin sheet of material to which is secured reinforcing members or strips. In the case of the top wall, shown more particularly in Fig. 2^a, the top is shown as comprising a thin sheet of material 4 to which is secured, as by gluing, a plurality of spaced reinforcing elements or strips 5, these strips being preferably of thin narrow material. In the case where the wall members, such as the sheet material 4, are of wood, it is preferable that the strips 5 be secured to the wood with the

grain of the strips transverse of the grain of the wall member, but this is not absolutely necessary. The bottom wall is identical with the top wall in construction, being reversed in position, so that the strips 5 will be presented toward the inside of the container.

Each side wall 2 comprises a thin sheet material 6 to which is secured, preferably longitudinally, a number of spaced reinforcing elements or strips 7. In the form of device where the top and bottom walls are connected to the side walls by interlocking joints, each side wall is provided with a number of notches 8, these notches being cut through both the side wall members 6 and the upper and lower reinforcing elements 7. It will thus be noted that when the top cover 1 is in place with the ends of the strips 5 fitting into the notches 8, the top and bottom walls will be connected to the side walls with a lock joint connection. It will also be noted that when the top and bottom walls are secured to, as by nails or staples, the side walls, the securing elements 9 may be driven through both the thin wall member 4 and the strips 5 as indicated at 9 in Fig. 1 of the drawings. Ordinarily when nails are driven through thin wood material the wood is apt to split. When the reinforcing strips are glued, as in this invention, to the wood, and the securing elements pass through both the wood and reinforcing strips, the latter prevents the wood from splitting. It is to be understood, however, that the thin wall members may not be made of wood, but may be of any other kind of thin material suitable for making containers of this kind. The end walls are preferably composed of each a thin sheet of material 11, to which is secured, at the boundaries of the sheet, reinforcing cleats 12 and 13, the cleats 12 being preferably the vertical cleats and the cleats 13 being preferably the horizontal cleats. The vertical and horizontal cleats are mortised and tenoned at respective ends, as clearly shown in Fig. 3 of the drawings. It will also be noted that the vertical cleats 12 are provided with notches 14 and 15 for the reception and securing thereto of the ends of the horizontal reinforcing elements 7 of the side walls. In order that the ends of the reinforcing elements or strips 7 may be properly received in the notches 14 and 15, the end wall member 11 is also provided with corresponding notches 16 and 17, as clearly shown in Fig. 3 of the drawings.

In the event that an end wall without reinforcing cleats be used in lieu of a wall 125 of a thin sheet material with reinforcing cleats, such end wall may be made of relatively thick material and of the form shown in Fig. 4 of the drawings.

One of the important features of the in-

vention is that the packages may be compactly packed inside of the container and yet be spaced away from the walls of the container so as to provide for air spaces both 5 for air circulation and for the protection of the goods when the container is handled with instruments such as hooks or when one container falls upon the other and has a tendency to bend or impart a shock to the 10 contents of the container. It will be apparent from this disclosure, that if the packages were in contact with the outside wall of the container, and the latter was to receive an impact or blow from an external 15 object, the impact would immediately be transmitted to the packages inside the container with a possible result of injuring the package, such as denting of cans when the packages are canned goods, or otherwise 20 make it easier to injure the container itself. The reinforcing members, besides being for the purpose of giving strength to the container, also serve the purpose of protecting the packages and also for providing air 25 spaces between the packages and the outside walls of the container.

In addition to the above and in the preferred form, the reinforcing members are so spaced on the bottom wall as well as on 30 the upper wall and along the sides of the side walls of the container, so that the adjacent edges of the packages will overlap the reinforcing strips so that the latter will act as supporting means for the packages 35 at their edges or boundaries. As for example, each bottom strip will lie under the adjacent edges of two rows of packages, as clearly shown in Fig. 5 of the drawings. It will be noted that the packages meet substantially 40 along a center line of each supporting strip 5. On the side walls, the upper and lower supporting strips will bear against the upper edge of the upper row of packages and the lower edge of the lower 45 row of packages respectively. The center strip 7 will overlap the lower edges and the upper edges of the top and lower rows of packages respectively. In this way it is impossible for the packages to be placed in 50 the container except in an upright and correct position. The packages must be placed in compact relation or it would be impossible to place the designated number of packages within the container without this arrangement being insured. While I consider the 55 above as the preferred form for this construction I do not wish to be limited to this identical arrangement, as other forms of construction might be used without departing from the spirit of my invention.

In the event that it be desired to increase the ventilation of the container, the side walls may be made without the notches shown in Fig. 2 of the drawing, but the 60 strips 5 of the top and bottom walls may

rest upon the upper and lower edges of the side walls 2, as clearly shown in Figs. 13 and 14 of the drawings, so as to provide air spaces or passages 18 between the top and bottom walls and the edges of the side walls. 70

In order to economize in the time of producing as well as cost of materials, the end wall members 11 may be made of slightly less length so as to bear against the sides of the reinforcing strips 7 without forming the 75 notches 16 and 17, and hence the intervening tongues 19 and 20 therebetween, as shown in Fig. 3. See for example the end wall members 11 of Figs. 8, 9 and 10.

In the structures above referred to, the 80 side walls are described with the reinforcing members 7 as disposed longitudinally of the side walls. If desired, the reinforcing members may be made in vertical disposition such as that shown in Figs. 11 and 12 of the 85 drawings. Inasmuch as the vertical reinforcing members 21 might be too narrow to receive the fastening means driven downwardly through the cover or upwardly through the bottom, as shown in Fig. 1, the 90 top and bottom walls may be suitably fastened to the side walls by the use of flexible binding material 22 bent about the corner of the box, so that a staple, nail or other like and similar fastening may be driven through 95 one end of the material 22 and through the top and bottom wall members and the reinforcing strips such as shown at 23, in Fig. 11 of the drawings, and a fastener 24 similarly driven through the other end of the 100 material and the side wall of the container, as shown in Figs. 10 and 11 of the drawings.

While I have shown and described my container as having walls comprising a single sheet of thin material, I wish it understood 105 that if desired I can construct such walls with two or more pieces laid either edge to edge or spaced apart, without departing from the spirit of my invention.

The walls of the container may be made 110 in large lots according to size and when it is desired to make the container, the walls may be selected and brought together conveniently to form the container. This makes the production of containers 115 economical.

While I have herein described and upon the drawings shown a few embodiments of the invention, it is to be understood that the invention is not limited to the particular details, arrangement of parts and construction described and shown, but that other details, arrangements of parts and constructions are comprehended by the invention without departing from the spirit thereof. 120

Having thus described my invention, I claim:

1. A shipping container for packages such as cans or cartons, comprising walls having thin wall members, and narrow reinforcing 130

strips rigidly secured to the wall members and so positioned relatively to each other as to strengthen the wall member, support all of the cans or cartons at their meeting edges on a plurality of the container walls, so that the cans or cartons will be compactly and securely disposed in said container, and provide air spaces between the cans or cartons and the inner faces of the wall members.

2. A shipping container for packages such as cans or cartons, comprising walls having thin wall members and a plurality of narrow reinforcing elements rigidly secured to said wall members and so spaced with relation to each other and positioned with respect to the adjacent edges of the cans or cartons as to support the cans or cartons at said edges on a plurality of said walls when said cans or cartons are packed in the container for supporting the cans or cartons rigidly and compactly in the container.

3. A container for packages such as cans or cartons, comprising walls having thin wall members and reinforcing strips glued to the wall members, the strips of adjacent walls meeting each other in overlapping manner so that securing elements may pass through one of the reinforcing strips and its wall member and into the adjacent strip without substantially splitting the material of the wall or strips, the strips being so positioned relatively to each other as to strengthen the wall member, support the packages and provide air spaces between the packages and the inner face of one or more of the wall members.

4. A shipping container for packages such as cans, cartons, and the like, comprising a plurality of walls having thin wall members normally easily split by fastening elements such as nails, and the like, and relatively

narrow reinforcing strips also normally easily split by such fastening elements, said strips being glued to the wall members, the marginal strip of one wall having notches to receive the adjacent ends of strips of an adjacent wall to permit the securing of one wall to the other by fastening means without substantial splitting of the material of the walls or strips, the strips being so positioned relatively to each other as to strengthen the wall member and support the cans, cartons and the like rigidly and compactly in the container.

5. A shipping container for packages, such as cans, cartons, or the like, comprising walls having wall members, reinforcing strips glued to the wall members, the strips of adjacent walls meeting each other at right angles, a plurality of walls being notched to receive the strips of the adjacent wall, the strips being so positioned as to strengthen the wall members, and support the packages rigidly and compactly in the container.

6. A container for packages comprising walls having thin wall members, and reinforcing strips secured to the wall members, the strips of adjacent walls meeting each other in overlapping manner so that securing elements may pass through one of the reinforcing strips and its wall member and into the adjacent strip without substantially splitting the material of the wall or strips, the strips being so positioned relatively to each other as to strengthen the wall member, support the packages and provide air spaces between the packages and the inner face of one or more of the wall members.

In witness whereof, I hereunto subscribe my name to this specification.

OLIVER M. BABCOCK.
